PHONOGRAPHIC DEVICE

Hubert L. Shortt, White Plains, N. Y., assignor to
 Polytron Corp., White Plains, N. Y., a corpora-
 tion of New York

Application March 15, 1946, Serial No. 654,655

4 Claims. (Cl. 274—23)

1

This invention relates to improvements in phonographic devices, and more specifically to an arm for supporting a phonograph reproducing device wherein the axis of the reproducing device is constantly maintained tangent to the record groove at the point of needle contact, and normal at the same point, to the record radius.

When such a tangency-normality condition obtains, the phonograph reproducer is actuated by the undulations of the record groove, without the introduction of a distortion factor, which would exist if the axis of the reproducer lay at an angle other than 90°, with respect to the radially recorded undulations of the record. That this is the case, and that therefore the angular relationship between the reproducer axis and the record groove is of utmost importance for a clear and faithful reproduction, is well known to persons skilled in the art. For reference, I quote an article by B. B. Bauer, "Tracking angle in phonograph pick-ups," in the March 1945 issue of "Electronics," page 110.

Several attempts have been made in the prior art to achieve tangency, but satisfactory results have not been obtained hitherto. The principle of devices of the prior art may be understood by means of the following considerations.

Picturing a conventional, single phonograph tone arm, pivoted at one point, it is seen that the reproducer it carries may be tangent to the groove for one, and only, particular value of the radius, that is of the distance from the stylus point to the center of the record, or of the turntable. For all other values of the radius, the reproducer will form an angle with the tangent. The possibility therefore suggests itself that such an angle may be compensated for through controlling cam means of a predetermined profile, in turn controlled by the tone arm, all of the controls requiring arrangements such as pulleys, associated with driving belts, concentric hollow shafts, roller followers, spring connections, and the like.

Devices of such a type, as well as others involving sliding contacts in conjunction with compensating grooves, roller mechanisms on rails capable of displacing the entire tone arm, and so on, are too cumbersome to handle, too expensive to manufacture, requiring costly precise machining operations, and mechanically unreliable. In general they do not achieve true tangency. If they get somewhat close to it, it is at the cost of providing structures complicated beyond any reasonable limit. Moreover, they cannot be adapted to operate in conjunction with modern automatic record changers, wherein the repro-

2

ducer supporting arm is the prime or base actuator of the entire mechanism, and must be solidly linked thereto.

Another problem with which this invention is concerned is the distribution of the horizontal frictional force created by the needle drag against the record. The establishment of an equilibrant force to offset the effects of this frictional force is a problem quite apart from reproducer tangency considerations, and an improved solution of this problem is an added feature of my invention.

The general object of my invention is to provide a phonograph reproducer supporting device which maintains the axis of the sound reproducer tangent to the record groove and normal to the record radius at the point of needle contact.

Another object is to provide a phonograph reproducer supporting device achieving the above general object, which device is simple, reliable, and easy to manufacture; does not include pre-formed cams, grooves, or pulley mechanisms; and comprises no parts requiring precise machining.

A further object is to provide such a phonograph reproducer supporting device which is easily adaptable for use in any modern automatic record changing phonograph.

A still further object is to provide means whereby the tangential drag of the needle in the record groove is apportioned among two anchor points.

Other related and ancillary objects will become apparent as the description proceeds.

My invention will be understood with reference to the appended drawings, wherein:

Fig. 1 is a plan view of a phonograph arm according to my invention, indicating part of a frame, a turntable, and a record thereon.

Fig. 2 is a front elevation of the assembly of Fig. 1.

Fig. 3 is a schematic representation of the same phonograph arm, wherein various symbols, used in the formulae which occur in the description, are graphically identified.

Fig. 4 is a schematic representation of the same phonograph arm, shown in broken lines in various positions, which together define the trajectory of the stylus point.

Referring in detail to the drawings, a turntable 1 of any conventional type is mounted on a suitable frame, of which the supporting board 2, partially shown, is a part, by means of a spindle 3 which is in turn driven by any type of phonograph motor desired. A standard record 4 is shown placed on the turntable 1 for purpose of

illustration only. The reproducer supporting arm is divided into two sections.

One end of the main or driver section 5 is mounted at 6 to base 7, the mounting at 6 being such that arm 5 pivots both vertically and laterally. Any conventional method may be used for this latter purpose. The second, or receiver section 8, is hinged or swiveled at 9 and moves only laterally with respect to the driver section 5. For the purpose of reproducing the undulations of the record groove any type of translating device 10 may be used, such as a standard crystal, a magnetic, or an electrostatic phonograph pickup. The translating device 10 is contained in the receiver section 8 as indicated. As will be shown later, the only mounting requirement is that the axis of the translating device coincide with a line running centrally through the receiver arm 8.

One end of a link bars 11, of any convenient form, is attached to a point 12 on the receiver arm 8 in any manner which permits a rotational movement with respect to receiver arm 8. The other end of the link bars 11 is pivoted at a point 13 on a rotating member 14 which I have chosen to call a "link coupler" for a very specific reason. This link coupler, in turn pivoted at 15 to the frame, may have any appearance or shape, artistic or otherwise, so long as pivots 13, 15 and 18 are spaced relative to each other as dictated by the other parameters of this mechanism.

One end of a final lever arm 16 is pivoted at a point 17 on the driver arm 5, in such a manner as to permit rotational movement with respect to driver arm 5. The other end of arm 16 pivots on the "link coupler" 14 at a point 18 determined by other parameters of this mechanism.

Link bars 11 and 16 have integral upstanding end projections at pivot points 12 and 17 and integral depending end projections at pivot points 13 and 18, and in connection with such structures I have provided slots in receiver arm 8 and driver arm 5 through which the upward extensions of the link bars at the respective pivot points pass; likewise I have provided slots in link coupler 14 into which depending end projections of link bars 11 and 16 pass at their respective pivot points, the extensions of the link bars at the respective pivot point being of sufficient length to permit a vertical movement of the driver arm at its pivot 6. It is not essential, however, that all four extensions have relative movement respective to the arms 5 and 8 or the link coupler, it being sufficient that depending extensions 13 and 18 be upwardly movable in relation to link coupler 14 while the extensions at pivot points 12 and 17 may be connected to the arms 5 and 8 only to provide the requisite lateral movement.

Examining now the described structure as a whole, with reference to the principles of the kinematics of mechanisms, it is seen that it constitutes a constrained kinematic chain. In fact, it consists of a number of links having pivotal connections each with at least two of the others, which links and connections may be considered as arranged in a closed cycle if the supporting frame of the phonograph, which is connected to the driver arm and the link coupler, is looked upon as one of the links, precisely, as the fixed link. The relation between the number of links and the number of joints is such that the chain is "constrained," that is has one degree of freedom, as can be seen by application of the elements of the kinematic theory.

The property of the chain of being con-

strained can be expressed also by stating that if the position of any link of the chain, chosen as a "driver bar," is fixed, (said driver bar being of course distinct from the fixed supporting frame), then the position of all the other links is also fixed, so that for each position of the driver bar any given point on the chain has one and only one possible position. This is equivalent to stating that, if the chain is caused to assume all the infinite possible positions of which its structure permits with respect to its fixed supporting frame, any given point of the chain will describe a linear trajectory. In what follows, I will regard the driver arm 5 as the driving bar of the chain; and the point I am concerned with is of course the needle point. When the needle rides from the periphery to the center of the record, driver arm 5 rotates clockwise with respect to its base 7, receiver arm 8 rotates counterclockwise with respect to driver arm 5, and link coupler 14 rotates counterclockwise with respect to the frame about its pivot 15. For my device to operate the way I want it the needle must then follow a trajectory at every point of which the receiver arm is orthogonal to the record radius. The radial component of the frictional force exerted by the needle on the groove then will be substantially eliminated, while at the same time the additional major pivotal point 15 will cooperate with the main pivot 6 to bear the remaining tangential frictional force.

In practice of course there is no driving force applied to the driver arm. What happens is that the needle point is guided by the record groove, and follows it. Therefore it is not necessary to enter into a discussion of the precise geometric type of the groove spiral. The device is adapted to operate with the practical record grooves, and is not limited to any particular spiral equation.

In the foregoing, I have made the statement based on theory, that for each position of the driver arm (chosen as driver bar) there is one and only one possible position of each point and link of my device. Hereafter I will translate this statement into a precise set of mathematical relations, having the purpose better to illustrate the operation of the device, and further, to show how the parameters of the device, that is the various constant linear dimensions and one constant angle thereof, enter into said operation. Precisely, I will take as my independent variable the angle which the driver arm makes with a certain fixed line, and I will show how the other variable angles and certain variable distances which identify the position of the various links and points of the chain may be expressed as function of the above independent variable only, said functions containing therein the parameters of the device. In this manner I will show that, by suitably choosing the parameters of the device, the form of those functions can be modified at will, which statement means that the trajectory of any chosen point of the chain may be made to conform to operational requirements.

Hereafter, I will refer in detail to Fig. 3. In this figure, the structure of Figs. 1 and 2 is schematized, representing each link with a straight line, the link coupler being represented with two angularly offset radii. Fixed imaginary lines on the supporting frame are shown in dot-and-dash lines, and variable imaginary lines in broken lines. The same numerals as in Figs. 1

and 2 are generally used to identify the various links and joints. In addition, English letter symbols denote lengths and Greek letter symbols denote angles.

Figure 4 shows the trajectory which needle point 19 must follow in order to be tangent to the record groove for each successive distance from the center of the record. It is

$$y=r \sin \xi \quad (1)$$

$$x=-r \cos \xi \quad (2)$$

or

$$y=-x \tan \xi \quad (3)$$

For mathematical reasons I introduce an imaginary line a , connecting points 9 and 3. Then

$$a^2=C^2+B^2-2BC \cos \theta \quad (4)$$

By definition arm 8 (line D), must be perpendicular to the radius r at point of needle contact, that is, the angle formed by arm 8 and the radius r must be a right angle at all times.

Hence

$$r^2=a^2-D^2 \quad (5)$$

Likewise

$$a^2=r^2+D^2 \quad (6)$$

Then

$$r^2+D^2=C^2+B^2-2BC \cos \theta \quad (7)$$

Or

$$\theta=\cos^{-1} \frac{C^2+B^2-D^2-r^2}{2BC} \quad (8)$$

Since C, B, and D are constants, angle θ is a univocal function of r . That is, for every value of r above the x axis, there is one and only one value of angle θ .

Likewise, angle ϕ above the x axis can have only one value for each value of angle θ since it is apparent that

$$\phi=\sin^{-1} \frac{D}{a} \quad (9)$$

By simple trigonometry,

$$\alpha=\cos^{-1} \frac{a^2+B^2-C^2}{2aB} \quad (10)$$

Now, angle Z is fixed by the location of point 6 with respect to point 3. Therefore angle α ,

$$\alpha=\lambda-Z \quad (11)$$

and the angle which r makes with the x axis is angle ξ .

$$\xi=\alpha+\phi \quad (12)$$

Substituting (9) and (10) in (12) we have

$$\xi=\cos^{-1} \frac{a^2+B^2-C^2}{2aB}-Z+\sin^{-1} \frac{D}{a} \quad (13)$$

We have shown so far that the two basic variables of our spiral Equations 1 and 2 are both functions of angle θ , viz:

$$\xi=f_1(\theta) \text{ by Equation 13}$$

$$r=f_2(\theta) \text{ by Equations 5 and 4}$$

It is now obvious that for every value of radius r and angle ξ , above the x axis, there can be one and only one value of angle θ , the angle which the driver arm 5 makes with imaginary line (B) drawn between point 6 and 3. In my invention I make very special use of this relation.

We have shown that angle ξ is, $\xi=f_1(\theta)$. For physical convenience it has been found necessary to pivot lever 11 at a point 12 somewhat removed from the point of needle contact. This creates

a new angle η with respect to the x axis. We now draw imaginary line (g) from point 12 to point 3.

$$g^2=r^2+H^2 \quad (14)$$

Line $g=f_3(\theta)$ since $r=f_2(\theta)$ and H is a constant.

$$\eta=\xi-\epsilon \quad (15)$$

$$\epsilon=\tan^{-1} \frac{H}{r} \quad (16)$$

Substitute (13) and (16) in (15), and angle η is

$$\eta=\cos^{-1} \frac{a^2+B^2-C^2}{2aB}-Z+\sin^{-1} \frac{D}{a}+\tan^{-1} \frac{H}{r} \quad (17)$$

remembering that $a^2=C^2+B^2-2BC \cos \theta$, and that C, B, D and H are constants, plus the fact that, $r^2=a^2-D^2=C^2+B^2-D^2-2BC \cos \theta$ then, $\eta=f_4(\theta)$ for given values of C, B, D , and H . That is angle η can have one and only one value for a given value of angle θ .

We now draw imaginary line (f) from point 15 to point 12 and set our equation.

$$f^2=E^2+g^2-2Eg \cos \eta \quad (18)$$

Since $g=f_3(\theta)$, and $\eta=f_4(\theta)$, we have

$$f=f_5(\theta) \quad (19)$$

that is, line (f) can have one and only one value for each value of angle θ , radius r remaining above the x axis. Moreover, (f) will have a maximum value when angle θ has a value other than its minimum or maximum. This maximum value of (f) is used to fix the total length of radius R on coupler 14 plus lever arm K or 11.

$$R+K=f \text{ max} \quad (20)$$

Any convenient ratio between R and K may be chosen. In the illustrated example a ratio of $K=5R$ was used to keep the size of the link coupler 14 to a small value.

Angle ξ is the angle made by radius R with the X axis.

$$\xi=\rho+\lambda \quad (21)$$

$$\rho=\sin^{-1} \left(g \frac{\sin \eta}{f} \right) \quad (22)$$

Since $g=f_3(\theta)$ and $f=f_5(\theta)$, then $\rho=f_6(\theta)$.

Further,

$$\gamma=\cos^{-1} \frac{R^2+f^2-K^2}{2Rf} \quad (23)$$

Because $f=f_5(\theta)$ and R and K are constants, Equation 21 is then $\xi=f_7(\theta)$.

If the rotation R is always in the same direction as angle θ moves from maximum to minimum, then angle ξ can have one and only one value for each value of angle θ . How the rotation of R is kept always in one direction will be shown later. Mathematically, we consider γ positive when R moves above the line (f) and negative when R moves below the line (f).

If we were to consider the starting point of R (as it rotates counterclockwise) to be that position which it assumes when angle θ is a minimum, and further consider that radius R is contained in coupler 14, then coupler 14 would be rotated a definite number of degrees for each new position of angle θ as it moves from minimum to maximum, or

$$\frac{d\xi}{d\theta}=f_8(\theta) \text{ only} \quad (24)$$

It will now be shown how angle ξ is forced to assume one and only one value for each value of

angle θ , which in turn means that needle point 19 must follow the trajectory

$$y = -x \operatorname{tg} \xi \quad (3)$$

Referring to Figure 3, imaginary line s is drawn from point 15 to point 17. Angle χ is a fixed angle formed by line B and line Q. Line W is the distance from point 17 to point 6. Angle μ is the angle contained between imaginary line Q and driver arm 5, (C.).

$$\mu = \chi - \theta \quad (25)$$

Since angle χ is fixed, $\mu = f_9(\theta)$ and

$$\frac{d\mu}{dr} = -\frac{d\theta}{dr} \quad (26)$$

or as θ decreases, μ increases. This relationship enables us to work below the x axis and to the left of the driver arm 5 with the same effectiveness as we did to the right of driver arm 5 above the x axis when moving arm 8 with respect to arm 5.

Now,

$$s^2 = Q^2 + W^2 - 2QW \cos \mu \quad (27)$$

Of course Q and W are constants and hence $s = f_{10}(\theta)$ because $\mu = f_9(\theta)$.

The angle which radius L would make with the x axis is shown as angle σ .

$$\sigma = \beta + \Sigma \quad (28)$$

Angle τ is a fixed angle formed at point 15 by line Q and the x axis, or line E.

$$\Sigma = \tau - \sigma \quad (29)$$

and angle σ ,

$$\sigma = \sin^{-1} \left(\frac{W}{s} \sin \mu \right) \quad (30)$$

or angle $\sigma = f_{11}(\theta)$ because $\mu = f_9(\theta)$.

Further, by connecting radius L to arm 5 by means of arm 16 or M, we have

$$\text{angle } \beta = \cos^{-1} \frac{L^2 + s^2 - M^2}{2Ls} \quad (31)$$

Since L and M are constants, and s is a function of angle θ by Equation 27, then angle $\beta = f_{12}(\theta)$.

Or, substituting (29), (30), and (31) in (28), we have

$$\sigma = \cos^{-1} \frac{L^2 + s^2 - M^2}{2Ls} + \tau - \sin^{-1} \left(\frac{W}{s} \sin \mu \right) \quad (32)$$

The rotation of link coupler 14 is kept continuous and always in the same direction as angle σ moves from maximum to minimum, or vice versa, by setting,

$$L + M = s \text{ max} \quad (33)$$

The line s will always have a maximum value when angle θ is minimum.

Further, it will be noted that the "dead center" points of cranks R, K, and L, M, do not occur at the same time and hence the mechanism cannot "lock" or change direction for a given movement of the driver arm 5. The angular displacement of points 15 and 18 is determined by the values of angles ξ and σ when line s is maximum and angle θ is a minimum, that is, the fixed angle between radii R and L is equal to the value of angle ξ plus angle σ when angle θ is a minimum.

If we consider the starting point of radius L (as it rotates counter clockwise) to be that position which it assumes when angle θ is a mini-

mum, and further consider that radius L is contained in coupler 14, then coupler 14 will be rotated a definite number of degrees for each new position of angle θ as angle θ moves from minimum to maximum, that is

$$\frac{d\sigma}{d\theta} = f_{13}(\theta) \text{ only} \quad (34)$$

Now it is obvious that radii R and L can be contained in coupler 14 if

$$\frac{d\sigma}{d\theta} = \frac{d\xi}{d\theta} \quad (35)$$

for all values of θ .

15 Another way of saying the same thing is to consider two rotating radii with a common origin, revolving at the same angular velocity, viz.

$$W_R = W_L \quad (36)$$

20 Then the two radii could be tied together, and that is exactly what is accomplished by the link coupler 14.

We have now developed a method of rotating coupler 14 by means of lever 16 for each value 25 of angle θ such that receiver arm 8 will be perpendicular to record radius r for all values of r .

The possible combinations of lever arm lengths, driver and receiver arm lengths, coupler sizes, mounting angles radii to lever arm ratios is beyond discussion here. There are many advantages in selecting regular relationships from a mathematical point of view. Consider Equation 10.

$$\lambda = \cos^{-1} \frac{a^2 + B^2 - C^2}{2aB} \quad (10)$$

If $C = B$, then triangle aBC is isosceles, and angle $\lambda = \text{angle } \Lambda$ then

$$2\lambda = 180^\circ - \theta \quad (37)$$

$$\lambda = \frac{180^\circ - \theta}{2}$$

Or

$$\cos^{-1} \frac{a^2 + B^2 - C^2}{2aB} = \frac{180^\circ - \theta}{2} \quad (38)$$

The location of link coupler 14, the selections of points 12 and 17 and the values of arms 5, 8, 11, and 16 are mathematically related to each other. There is almost an infinite number of combinations of radius L, lever arm M, point 17, and the displacement angle between radius L and radius R. One or more of these combinations may be used to rotate link coupler 14 as a function of angle θ such that needle point 19 follows the spiral.

My invention may be considered in effect a four bar chain. This is easily seen by visualizing the four bars as shown in Figure 3 and remembering that bars s and f have instantaneous values as functions of angle θ .

Apart from the necessity of mounting the reproducer arm 8 to the driver arm 5 so that it pivots at point 9, only three punch press parts 65 are required to modify a standard phonograph supporting arm to a mechanism of this type, viz., lever arms 16 and 11 and coupler 14.

It is to be understood that the foregoing description and mathematical discussions have been offered merely by way of illustration and interpretation and that many changes may be made in the arrangement and proportions of my device without departing from the spirit of the invention or exceeding the scope of the appended 70 claims.

I claim:

1. In a phonograph, in combination with a frame a grooved record rotatable on said frame and a stylus-mounting sound reproducing device, wherein said sound reproducing device is mounted on a kinematic chain in such position that at every point of the trajectory of the stylus it mounts said reproducing device tangent to the record groove engaged by said stylus a receiver arm carrying said sound reproducing device, a driver arm pivotally anchored to said frame and pivotally connected to said receiver arm, a link member pivotally anchored to said frame, a first connecting member pivotally connected to said link member and to said receiver arm at a point intermediate the ends of this latter, and a second connecting member pivotally connected to said link member and to said driver arm at a point intermediate the ends of this latter.

2. In a phonograph, in combination with a frame carrying a turntable upon which is supported a grooved record and a stylus-mounting sound reproducing device, wherein said sound reproducing device is mounted on a kinematic chain in such position that at every point of the trajectory of the stylus it mounts said reproducing device tangent to the record groove engaged by said stylus a receiver arm carrying said sound reproducing device; a driver arm anchored to the frame so as to swing with respect thereto both in a plane parallel and in a plane perpendicular to the turntable and pivotally connected to said receiver arm; a first connecting member pivotally connected to said receiver arm at a point intermediate the ends of this latter and pivotally connected to a first crank arm, this latter being pivotally anchored to the frame; and a second connecting member pivotally connected to said driver arm at a point intermediate the ends of this latter and pivotally connected to a second crank arm, which second crank arm is pivotally anchored to said frame at the same point at which said first crank arm is anchored; said first and second crank arm being rigidly connected so that the angle therebetween remains constant; the lengths of the said crank arms, the distances between the pivotal connections of said various aforementioned members, and the distances between the points at which said driver arm and said crank arms are anchored to said frame and the point about which the turntable revolves, being so related that as the stylus moves in the record groove said receiver arm remains perpendicular to the line from the point of the stylus to the center of the turntable.

3. In a phonograph, in combination with a frame a grooved record rotatable on said frame and a stylus-mounting sound reproducing device, wherein said sound reproducing device is mounted on a kinematic chain in such position that at every point of the trajectory of the stylus it mounts said reproducing device tangent to the record groove engaged by said stylus a driver arm pivoted to the frame; a receiver arm pivoted to said driver arm and carrying said sound repro-

ducing device; a link member pivoted to the frame; a first link bar connecting said driver arm and said link member in such a way that when the former is displaced clockwise with respect to the frame the latter is displaced counterclockwise with respect to the frame; and a second link bar connecting said link member and said receiver arm in such a way that when the former is displaced counterclockwise with respect to the frame the latter is displaced counterclockwise with respect to said driver arm, and is thereby maintained tangent to the record groove at the point at which the stylus engages said groove.

4. In a phonograph, in combination with a frame carrying a turntable upon which is supported a grooved record and a stylus-mounting sound reproducing device, wherein said sound reproducing device is mounted on a kinematic chain in such position that at every point of the trajectory of the stylus it mounts said reproducing device tangent to the record groove engaged by said stylus, a receiver arm carrying said sound reproducing device; a driver arm anchored to the frame so as to swing with respect thereto both in a plane parallel and in a plane perpendicular to the turntable and pivotally connected to said receiver arm; a first connecting member pivotally connected to said receiver arm at a point intermediate the ends of this latter and pivotally connected to a first crank arm, this latter being pivotally anchored to the frame; and a second connecting member pivotally connected to said driver arm at a point intermediate the ends of this latter and pivotally connected to a second crank arm, which second crank arm is pivotally anchored to said frame at the same point at which said first crank arm is anchored; said first and second crank arm being rigidly connected so that the angle therebetween remains constant; said first crank arm and first connecting member reaching their dead center relative position when said second crank arm and second connecting member are at an angle to their dead center relative position; the lengths of the said crank arm, the distances between the pivotal connections of said various aforementioned members, and the distances between the points at which said driver arm and said crank arms are anchored to said frame and the point about which the turntable revolves, being so related that as the stylus moves in the record groove said receiver arm remains perpendicular to the line from the point of the stylus to the center of the turntable.
